OIL-POT FOR VERTICAL-SHAFT MACHINES

René A. Baudry and Garfield E. Peterson, Pittsburgh, Pa., assignors to Westinghouse Electric Corporation, East Pittsburgh, Pa., a corporation of Pennsylvania

Application June 29, 1950, Serial No. 171,212

2 Claims. (Cl. 308—134.1)

1

Our invention relates to bearing-assemblies for vertical-shaft machines, comprising a stationarily mounted oil-pot which has an inner standpipe around the shaft.

It has been found that there has frequently been oil-leakage down the vertical shafts of such machines, particularly in the high-speed machines. To discover the cause of this leakage, it was necessary to build a test-machine with transparent parts, so that the oil-circulation about the standpipe could be observed and studied. It was found that the runner which dips down into the oil in the oil-pot had a pumping-action, tending to throw out the oil centrifugally along the bottom face of the runner, and thus sucking the oil away from the inner diameter of the runner. This pumping-action drew out the oil from the space between the inner diameter of the runner and the outer diameter of the inner standpipe, depressing the oil-level at this place, down to the bottom of the runner, thus causing air to be sucked in, and in a few seconds all of the oil in the pot was transferred into foam and froth, which would build up and leak out over the top of the inner standpipe.

Our present invention is directed to a provision of suitable sealing-means for preventing the action just described. More particularly, it is an object of our invention to provide a spaced sealing-ring, disposed in the space between the lower end of the inner diameter of the runner and the inner standpipe of the oil-pot, with means for providing a substantially free oil-communication from the main body of oil in the oil-pot to the inner diameter of the sealing-ring at the bottom of said ring, and thence over the top of said ring, and also with means for impeding the downward flow of oil in the space between the outer diameter of the sealing-ring and the lower portion of the inner diameter of the runner.

With the foregoing and other objects in view, our invention consists of the machines, combinations, systems, parts, and methods of design and operation, hereinafter described and claimed, and illustrated in the accompanying drawing, where-

in:

Figure 1 is the fragmentary vertical sectional view of the upper bearing-assembly having Kingsbury thrust bearings and a guide bearing, showing the manner of use of our new sealing-means;

Fig. 2 is a detail of the sealing-means which is used in Fig. 1; and

Fig. 3 is a vertical sectional view of a guide-bearing assembly for a vertical-shaft machine, embodying our invention.

2

Referring more particularly to Figs. 1 and 2, we have shown the top end of a vertical-shaft water-wheel generator, comprising a stator member which is represented by an upper bracket 4 which is shown fragmentarily at the bottom of Fig. 1, and a rotor member which is represented by the top end of a vertical shaft 5. The frame bracket 4 supports an oil-pot 6, which comprises an inner standpipe 7 and an outer standpipe 8, both mounted on top of the top plate 9 of the bracket 4. The inner standpipe 7 surrounds the shaft 5, with a small space therebetween.

The top end of the shaft carries a runner-bushing or thrust-block 14, which rotates with the shaft. Secured to, and abutting up against, the runner-bushing 14 is a runner 15, which is supported by resting on top of the thrust-bearing shoes 16, which are shown as being tiltably mounted on jack-screws 17 which are supported by the top plate 9 of the bracket, which also constitutes the bottom plate of the oil-pot 6. A filling of oil is provided, in the oil-pot 6, up to a cold oil-level 18, which rises up to a hot oil-level 19, which is limited by the top of an overflow-pipe 20. The normal hot and cold oil-levels 19 and 18 occur at an intermediate point in the vertical thickness of the runner 15, and of course necessarily below the tops of the standpipes 7 and 8.

30 In the particular bearing-assembly shown in Fig. 1, the outer periphery of the thrust-bearing runner 14 serves also as a runner for a guide-bearing 22, which is suitably supported from a top-structure 23 which is provided for the oil-pot 6. This top-structure 23 also includes a seal 24 which cooperates with the outer periphery of the runner-bushing 14.

Surmounting the top end of the shaft 5 and the runner-bushing 14, in Fig. 1, is a suitable cover 25.

40 The oil in the oil-pot 6 is cooled by suitable means, represented in the drawing by cooling-coils 26. Other well known details of oil-pots of this nature have been omitted, in the interests of clarifying the description of our present improvements.

45 In accordance with our present invention, we provide means for preventing oil-leakage in the space between the top of the inner standpipe 7 and the downwardly depending inner diameter of the runner 15. Our preferred form of means, which is used for taking care of the most stubborn cases of oil-leakage, provides two restricted spaces, or oil-seals, both disposed within the space between the standpipe 7 and the inner diameter of the runner 15. Under certain circumstances, we may use only one of these seals.

As shown more in detail in Fig. 2, we provide, in the space between the outer diameter of the inner standpipe 7 and the lower portion of the inner diameter of the runner 15, a spaced stationary sealing-ring 30. The upper portion of the sealing-ring 30 has a relatively small radial clearance t from the inner diameter of the runner 15. The inner diameter of the ring 30 has a larger radial clearance 32 from the outer diameter of the inner standpipe 7. The ring 30 also has a lower portion 33 which extends below the bottom of the runner 15. The lower end of the ring 30 is in relatively free communication with the main body of oil in the oil-pot 6, so that oil can freely flow under the bottom of the ring 30, up through the radial clearance 32 at the inner diameter of the ring 30, and thence over the top of the ring, so as to feed oil freely to the top of the small radial clearance t .

This small radial clearance t between the ring 30 and the runner 15 acts as an oil-impeding restricted-passage sealing-means for substantially impeding the downward flow of oil in the space between the outer diameter of the sealing-ring 30 and the lower portion of the inner diameter of the runner 15. This small radial clearance t is perhaps the simplest form of an oil-impeding sealing-means for this purpose. It will be understood, of course, that other, or more elaborate, means may be provided for the same purpose. This oil-impeding sealing-means t thus reduces the rate of downward oil-flow in this space, in response to the pumping-action of the runner 15, to a rate which is considerably lower than the available rate of oil-supply in the free-communication spaces which are provided from the main body of oil under, and back of, and over the top of, the sealing-ring 30.

Any suitable means may be provided for stationarily supporting the spaced sealing-ring 30, with or without some freedom of self-centering adjustment. In the specific form of our invention which is shown in Fig. 2, this means may be in the form of a few loosely fitting spacer-blocks 34 and 34', at spaced points around the outer diameter and at the bottom of the inner standpipe 7, with a loosely fitting pin or pins 34" for preventing rotation of the ring 30, while permitting the ring to center itself concentrically so as to provide a uniform restricted gap t at all points around it.

A second oil-impeding sealing-means t' is provided above the top of the sealing-ring 30 and below the normal oil-level 18 or 19 in the oil-pot 6. This second oil-impeding sealing-means t' is provided for substantially impeding the downward flow of oil in the space between the outer diameter of the inner standpipe 7 and an intermediate portion of the inner diameter of the runner 15, at a point which is spaced above the sealing-ring 30, and below the normal oil-level in the oil-pot. As a matter of convenience in construction, this second restricted radial clearance t' is provided by a ring 35 which is secured to the outer surface of the standpipe 7, so as to constitute, in effect, an enlargement or shoulder on the standpipe. However, this ring or shoulder 35 might have been attached to the inner diameter of the runner 15, so that the second restricted radial clearance t' would then be provided between the inner diameter of the ring 35 and the outer diameter of the standpipe 7. It will be understood, of course, that the ring 35 might be integral with the part to which it is attached. The essential thing, of course, is that some suit-

able means should be provided for substantially impeding the downward flow of oil in the space between the stationary standpipe 7 and the rotating runner 15.

In order for the restricted radial clearance t or t' to serve properly as a seal, without the formation of foam, it is necessary that the rotating oil-flow in this clearance shall be laminar. This matter has been investigated and discussed by G. I. Taylor, in an article on "The stability of a viscous liquid," Transactions of the Royal Society of London, Series A, volume 223, 1923, page 289, and Taylor's conclusions have been verified by our own experiments. The limiting condition for laminar flow in the seal-gap t or t' is the Reynolds number. In our tests, we have found that the critical Reynolds number is between 1000 and 1300, and occasionally higher Reynolds numbers up to 1800 or 2000. Between these limits, we have sometimes found turbulent flow, and sometimes laminar flow, depending upon other conditions. For the most part, if the Reynolds number is below 1000, laminar flow will be obtained; but, to provide a factor of safety, a Reynolds number of 800 represents a safer design-condition.

The Reynolds number N_R may be calculated from the formula

$$N_R = tV/r$$

where t =the thickness of the gap or radial clearance, V =the speed or velocity of the inner diameter of the runner 15 or other rotating member, and r =the kinematic viscosity of the oil.

If we set the maximum allowable Reynolds number N_R at 1000, it will be readily seen that the gap-thickness of the small radial clearance t or t' must be smaller than $1,000 r/V$. Ordinarily it will be found that this gap or small radial clearance t or t' will be so small that it is desirable to use as large a gap as possible, without running the risk of turbulent flow. A safe and preferable design-condition, therefore, would be to make this small radial clearance t or t' of the order of $800 r/V$. Gaps t of 0.04 to 0.16 inch are used in practical applications of our invention to vertical generators.

In the operation of our novel bearing-seal which is shown in Figs. 1 and 2, it will be noted that the pumping action of the runner 15, in tending to cause oil to flow radially away from the inner diameter of said runner, cannot drain off all of the inner-space oil by drawing the oil downwardly in either one of the small radial spaces t' or t , because provision is made for supplying oil freely to the bottom of the top radial clearance t' , or to the top of the bottom radial clearance t , faster than oil can be drawn downwardly through these seals. In this way, we prevent the oil-level inside of the inner diameter of the runner 15 from being dropped to the bottom of the runner 15, and hence we prevent the formation of the foam and froth which has previously resulted in occasions of oil-leakage over the top of the inner standpipe 7 and thence down along the shaft 5.

In the form of our invention which is shown in Fig. 3, the construction is similar, except that the runner-bushing 14 and the runner 15 of Fig. 1 have been combined in a single integral runner 44, having a depending portion 45 which extends underneath the oil-level 46. In the bearing-assembly which is shown in Fig. 3, the outer diameter of the depending runner-portion 45 is engaged by a guide-bearing 47; and no thrust-bearing is provided.

In Fig. 3, the inner standpipe 7' is spaced at all points by a considerable radial spacing from the inner diameter of the depending runner-portion 45, and the lower end of this radial spacing is occupied by a sealing-ring 30', which is supported on a few depending brackets 48 which are carried by the guide-bearing 47. The sealing-ring 30' is provided, as before, with a small radial clearance t with respect to the inner diameter of the depending runner portion 45, while a larger radial clearance 32 is provided between the sealing-ring 30' and the inner standpipe 7'.

The operation of the bearing-assembly shown in Fig. 3 is otherwise the same as that which has been described for Figs. 1 and 2, except that it will be noted that the second or upper oil-impeding sealing-means or restricted radial clearance t' of Figs. 1 and 2 has been omitted, in Fig. 3, as being an unnecessary refinement, in this case.

While we have discussed our invention in connection with two illustrative forms of embodiment, we wish it to be understood that we are not limited to these particular forms, as various equivalents may be substituted, in place of the precise structures which we have illustrated, and also certain parts may be omitted or added, within the contemplated scope of our invention. We desire, therefore, that the appended claims shall be accorded the broadest construction consistent with their language.

We claim as our invention:

1. A bearing-assembly for a vertical-shaft machine, comprising a stationarily mounted oil-pot including an inner standpipe surrounding the shaft in spaced relation to the shaft, a bearing-runner, means for mounting the top part of said runner so that it is carried by the shaft and rotates therewith, the lower part of said runner being below the normal oil-level in the oil-pot, and a bearing cooperating with said runner, characterized by a spaced stationary sealing-ring carried by said oil-pot between the outer diameter of said standpipe and the lower portion of the inner diameter of said runner, below the normal oil-level in the oil-pot, means for providing relatively free oil-communication from the main body of oil in said oil-pot to the inner diameter of said ring at the bottom of said ring, and thence over the top of said ring, means for providing an oil-impeding restricted-passage sealing-means for substantially impeding the downward flow of oil in the space between the

outer diameter of the standpipe and an intermediate portion of the inner diameter of the runner, below the normal oil-level in said oil-pot and above the top of said ring, and means for providing an oil-impeding restricted-passage sealing-means for substantially impeding the downward flow of oil in the space between the outer diameter of the ring and the lower portion of the inner diameter of the runner.

5 10 15 20 25 30 35 40 45

2. A bearing-assembly for a vertical-shaft machine, comprising a stationarily mounted oil-pot including an inner standpipe surrounding the shaft in spaced relation to the shaft, a bearing-runner, means for mounting the top part of said runner so that it is carried by the shaft and rotates therewith, the lower part of said runner being below the normal oil-level in the oil-pot, and a bearing cooperating with said runner, characterized by a relatively large radial clearance between the lower part of the inner diameter of said runner and the outer diameter of said standpipe, and a relatively small radial clearance between a higher part of the inner diameter of the runner and the outer diameter of the standpipe, the bottom of said higher part being below the normal oil-level in the oil-pot, and a spaced stationary sealing-ring carried by said oil-pot within said relatively large radial clearance, said ring having an upper portion having a relatively small radial clearance from the inner diameter of said runner, all portions of said ring having a larger radial clearance from the outer diameter of said standpipe, as compared to said small radial clearances, the bottom end of said last-mentioned larger radial clearance being in relatively free communication with the main body of oil in the oil-pot, the top of said ring being well below the top of said relatively large radial clearance between the runner and the standpipe, and said ring having a lower portion extending below said runner.
